UNITED STATES PATENT OFFICE.

CHARLES B. HALL, OF OAKLAND, CALIFORNIA.

DAVENPORT-BED.

1,303,473.

Specification of Letters Patent.

Patented May 13, 1919.

Application filed February 7, 1918. Serial No. 215,739.

To all whom it may concern:

Be it known that I, CHARLES B. HALL, a citizen of the United States, residing at Oakland, in the county of Alameda and State 5 of California, have invented new and useful Improvements in Davenport-Beds, of which the following is a specification.

This invention relates to a davenport bed.

One of the objects of the present invention is to provide a simple, substantial, light-weight davenport, in which a bed is provided without employing either the seat or back cushions, said bed comprising a folding frame supporting a wire mattress 15 and bedding, all of which is adapted to be concealed in the back rest of the davenport, as will hereinafter be described.

Another object of the invention is to provide a structure which is readily dismantled 20 for transportation or otherwise, and which is easily extended or folded in actual use.

Further objects will hereinafter appear.

The invention consists of the parts and the construction and combination of parts 25 as hereinafter more fully described and claimed, having reference to the accompanying drawings, in which—

Figure 1 is a plan view of the davenport, showing the bed-frame in horizontal position.

Fig. 2 is a cross section of the davenport, showing the bed-frame in vertical folded position.

Fig. 3 is a similar section, showing the 35 bed-frame in horizontal or extended position.

Fig. 4 is a side elevation of the leg hinge.

Fig. 5 is a front view of same.

Fig. 6 is a detail perspective view of the 40 latch 45.

Referring to the drawings in detail, A indicates the davenport frame which consists of a pair of end sections, such as indicated at 2, and a bedding box section 3 by 45 which they are connected. The bedding-box is comparatively long and narrow, as shown, and is provided with an upholstered cover section 4 which is hingedly secured to a back rest 9, as at 5. Secured to each 50 end frame, at a point intermediate the box 3, is a bracket plate 6 which supports the pivot pin 7; and pivotally mounted on each pin 7 is an arm 8, which arms support the back rest generally indicated at 9. This 55 back rest is upholstered, as at 10, on its forward side and is open on the rear side to

receive a mattress frame, generally indicated at B. This frame consists of a main section 11, an intermediate section 12 and an end section 14; the sections 11, 12 and 14 being pivotally connected, as at 15 and 16.

Secured to the intermediate section 12 and extending from end to end lengthwise of the bed is a truss frame 17, and pivotally attached to a bracket plate 18 secured on each end of the section 12 is a pair of hook-shaped links 19. The hooked ends of these links engage pins 20 formed on bracket plates 21 secured on the lower end and on each side of the back rest frame. These plates are also provided with lugs 21^a which support the main frame 11 in the folded position (see Fig. 2) while the pins 20 support said frame in the extended position (see Fig. 3).

Secured on the inner face of each end frame 2 of the davenport is a bracket in which is formed a channel 22. The channels are substantially straight while the upper ends are extended horizontally, as at 24, 80 to form a support for a pair of rollers 25 carried by the end frame 14. The rollers 25 are secured, one at each end of the end frame, and as they are sufficiently long to extend into the channel brackets, it is obvious 85 that they will be guided thereby.

Formed at the upper end of each channel 22 is a rod extension 26 adapted to engage a stop lug 28 secured at each end of the end frame 14. Secured at each end of the back 90 rest, interiorly thereof, is a bearing 30 in which is pivotally mounted a shoe 31; each shoe being provided with a slotted, segmental extension 32, through which extends one end of a link 33, the opposite end of 95 each link being pivotally secured, as at 34, to a leg 35 which is hingedly secured to the front or upper end 36 of the back rest. The hinge 37, by which each leg 35 is secured, forms one of the important features 100 of the present invention, as the construction shown permits each leg to swing in an arc of 270°.

By referring to Fig. 4, it will be seen that each hinge consists of a bracket plate 38 105 which is adapted to be secured on the inner face of the member 36. The upper end of this plate is angular, as at 39, and is provided with a hinge lug 40. The opposite plate of the hinge to which the leg 35 is 110 secured consists of a plate 41 which is offset at 42 to form a stop for the leg. The un-

per face of this offset is beveled, as at 43, to conform with the angle 39 of the opposite plate, and two arms are then extended, as at 44, to support the hinge lugs 45. These 5 lugs are sufficiently spaced to permit the insertion of the hinge lug 40, and a pin 46 extending through said lugs permanently connects same and permits the leg to be swung through an arc of 270°; the limit of 10 said swinging movement being obtained in one direction when the leg 35 assumes the vertical position shown in Fig. 2 and in the opposite direction when the beveled face 43 engages the angular upper end 39 of the 15 bracket plate 38, as shown by the dotted line position in Fig. 4.

The mattress frame, consisting of the sections 11, 12 and 14, is provided for the purpose of supporting an ordinary wire mattress spring, such as shown in Fig. 1, which is adapted to receive a mattress and bedding, the frame when folded assuming the vertical position shown in Fig. 2 and when extended the horizontal position shown in Fig. 20

25 3. With the bed in this latter position it can be seen that the intermediate section is supported by the pins 20 and that one side of the bed is supported by means of the legs 35, while the opposite side is supported 30 by the rollers 25, which in this position have entered the horizontal extension 24 of the channels 22. The legs 35, secured to the back rest by means of the hinges 37, as previously described, may either assume the 35 vertical position shown in Fig. 2, or may be folded over the bedding to assume the horizontal position, when the bed is folded. This movement of the legs 35 is utilized to raise and lower the main frame section 11 40 of the mattress frame within the back rest; that is, the links 33, connecting the individual shoes 31 with the legs, will cause each shoe to be swung from the dotted line position shown at 31^a (see Fig. 3) to the 45 full line position 31, the full line position being assumed when the legs are unfolded to support the bed, while the dotted line position is assumed when the legs are folded over the bedding. The mattress frame 50 proper is in this manner raised or lowered within the back rest and considerable more space is allowed for the reception of the bedding when the folded vertical position is assumed.

55 4. If it is desired to fold the bed, it is only necessary to swing the legs 35 into a horizontal position over the bedding. This, as previously described, lowers the shoes 31 and consequently permits the mattress frame to 60 recede within the back rest. The forward end of the back rest is then grasped and swung about the pivot 7 in the direction of arrow *a* until the vertical position shown in Fig. 2 is assumed. This swinging movement of the back rest will first cause the

65 lugs 28 to engage the rod extensions 27 and will at the same time force the rollers 25 back into the recesses 26 in alignment with the main channels 22. The frame sections 12 and 14 will at the same time swing about 70 their pivots or break joints. In other words, a positive mechanical operation is employed to break the hinge connections 15 and 12 when the bed is to be folded. A continued swinging movement in the direction of arrow *a* will cause the rollers to travel down through the channels 22 and will at the same time permit the links 19, together with the truss frame 17, to swing and assume the 75 position shown at 17^a. The bracket plates 80 will here engage the inwardly extending lugs 21^a and will, therefore, limit the swinging movement of the links 19 and also prevent the main section of the bed frame from dropping down through the lower end of 85 the back rest when the vertical position is assumed. The limited downward travel of the rollers 25 is determined by the length of the channels 22 and it is, therefore, possible to fold the frame sections 12 and 14 to 90 any angle desired by merely increasing or decreasing the length of said channels.

95 In the present instance, it will be seen that the frame section 12 practically assumes a right angle with relation to the main section 11 and that the section 14 again assumes, practically speaking, a right angled position with relation to the frame section 12. This causes the mattress and bedding carried by the frame to be folded or bent 100 at this point and also to be supported; the upper portion of the bedding being held in position by means of the legs 35 which were folded over the bedding, as previously described.

105 The arms 8 employed permit the back rest to be swung to assume a vertical position behind the stationary box section 4 and to assume a horizontal position above the box section when the bed is to be employed. The 110 cushions 4 and 10 are, therefore, never employed when the bed is in use. A comfortable seat or couch is provided during the day which has no appearance of a bed, while a full width bed is provided when the back rest is turned into the horizontal position.

115 The folding sections 12 and 14 are of 120 considerable importance as these permit the employment of a full width bed that could otherwise not be secured without increasing the height of the back rest to such an extent that the looks and design of the davenport would be practically destroyed. The depth of the davenport frame would naturally also increase in proportion to the height of the 125 back rest. The present structure permits a comparatively compact and light construction which is easily swung from one position to the other; the mattress and bedding being always exposed to the air as sufficient 130

space is provided between the wall and the bedding to permit a perfect circulation which maintains the bedding in a sanitary condition.

5 By referring to Figs. 2 and 3, it will be seen that both the arms 8 and links 19 are hook-shaped to engage their respective pins. This is of considerable importance as it permits the bed structure as a whole to be easily 10 dismantled for transportation or otherwise and also permits it to be passed through small doors that could not possibly be entered otherwise.

By referring to Figs. 2 and 3, it will be 15 seen that the upholstered section or cover 4 of the seat is hingedly secured to the back rest 9, as at 5, by means of a pair of arms 5^a disposed one at each end of the seat. One end of each arm is rigidly secured to the 20 seat while the opposite end is slotted to engage a pin 5^b secured on the back rest. This slot construction permits the seat to be quickly dismantled or moved with relation to the back rest.

25 By referring to Fig. 3 it will also be seen that the upholstered cover section 4 moves forward away from the box 3 when the back rest is swung into the horizontal position. This is due to the fact that the seat is supported by the back rest and also because it is first swung into the vertical position about the pins 5^a, shown by dotted lines 4^a in Fig. 2. It is secured in this vertical position by means of a strap 6^a which may be quickly 35 attached or removed, said strap having one end secured to the frame of the back rest as shown. The movement of the cover section 4 from the position shown in Fig. 2 to the position shown in Fig. 3 is of considerable 40 importance as it permits the mattress frame to assume a lower position than would otherwise be possible, the height of the mattress frame from the floor being in this instance limited by the height of the box and the 45 depth of the back rest frame in which the mattress frame is mounted.

For the purpose of relieving the weight of the members when they are unfolded and extended, a counterbalancing or tensioning 50 spring 40 has been provided. This spring may be mounted within the box 3 or directly under the same, as shown. The ends of the spring are attached to cords, such as shown at 41, one on each side of the frame, 55 which pass over directing pulleys, such as shown at 42. The opposite end of each cord being attached to the back rest at 43 pulls the spring and places it under tension when the bed is extended and thereby serves as a 60 means for counterbalancing the weight of the movable parts. It is, therefore, comparatively easy for any one to open and close the bed.

The legs 35 perform three functions: first,

they serve as a support for the bed when 65 this is extended; second, they serve as a means for raising and lowering the outer end of the bed frame with relation to the back rest; and, third, they serve as a bed clamp inasmuch as they engage the bedding 70 when it is folded over the frame. The bedding is held in the folded position by means of a pair of floating latches 45 positioned one on each side of the frame; that is, the latches are permitted vertical movement but 75 are locked against turning except in the extreme upper position. This is accomplished by guiding each latch member vertically and forming a projection on the lower end, as indicated at 46, which travels in the slot 47 80 formed in a plate 48. This plate is also slotted horizontally, as at 49, to permit the latch to be turned when the extreme upper position is reached, as shown in Fig. 3. It is only necessary to turn the latch in this 85 position to swing its upper hooked end into or out of engagement with the legs.

The reason for providing a free vertical movement of the latches is to permit these to rise and fall with the main frame section 90 11 as this is raised or lowered by means of the latch 31. The bedding clamped between the main frame 11 and the legs is thus secured whether the frame 11 is raised or lowered as the legs of the latches 45 rise and 95 fall in unison with same. The davenport when folded forms a comfortable seat or couch with absolutely no appearance of a bed. It is, furthermore, provided with a box 3 in which may be stored extra bedding, pillows and the like, and as this may be constructed of cedar and provided with an extra cover if desired, it may be used for 100 practically any purpose desired.

The simplicity of the parts employed 105 throughout produces a light-weight, compact, durable bed which is easily extended or folded and as the mattress frame is supported whether it is folded or extended, it is obvious that locks of any nature for the 110 purpose of locking it against refolding are unnecessary. Neither the back nor the seat cushions are employed when the bed is extended. These should, therefore, last comparatively longer as they are merely used 115 when the davenport is used as a seat.

The channelled guides 22 serve as a support for the inner end of the mattress frame both in the folded and in the extended position and as a guide for the frame during 120 the folding or extending operation. The lugs 28 on the frame force the rollers into and out of the lateral extensions in the channel, thus rendering the operation absolutely automatic. The inner end section is 125 supported entirely by the rollers, the intermediate section by the pins 20 and the main section by the shoes 31. A substantially

three-point support is thus provided which renders the bed frame exceedingly rigid when extended.

The materials and finish of the several parts of the device are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. A davenport comprising a pair of end frames, a box section connecting said frames, a back rest pivotally mounted between the end frames adapted to be swung to assume either a horizontal position above and forward of the box or a substantially vertical position behind box, a mattress frame mounted on the rear side of the back rest, said frame comprising a main section, an intermediate section and an end section, said sections being pivotally connected, a pair of hook-shaped links pivotally secured to the intermediate section, one at each end, engaging pins for the hooks secured to the back rest, a pair of rollers mounted on the end section, one at each end, a bracket having a guiding channel formed therein secured to each end frame of the davenport, said rollers extending into the channels and guided thereby, an offset formed in the upper end of each channel section adapted to receive the rollers and support the end frame when the mattress frame assumes a horizontal position.

2. A davenport comprising a pair of end frames, a box section connecting said frames, a back rest pivotally mounted between the end frames adapted to be swung to assume either a horizontal position above and forward of the box or a substantially vertical position behind the box, a mattress frame mounted on the rear side of the back rest, said frame comprising a main section, an intermediate section and an end section, said sections being pivotally connected, a pair of hook-shaped links pivotally secured to the intermediate section, one at each end, engaging pins for the hooks secured to the back rest, a pair of rollers mounted on the end section, one at each end, a bracket having a guiding channel formed therein secured to each end frame of the davenport, said rollers extending into the channels and guided thereby, an offset formed in the upper end of each channel section adapted to receive the rollers and support the end frame when the mattress frame assumes a horizontal position, and means for raising

and lowering the main section of the mattress frame within the back rest.

3. A davenport comprising a pair of end frames, a box section connecting said frames, a back rest pivotally mounted between the end frames adapted to be swung to assume either a horizontal position above and forward of the box or a substantially vertical position behind the box, a mattress frame mounted on the rear side of the back rest, said frame comprising a main section, an intermediate section and an end section, said sections being pivotally connected, a pair of hook-shaped links pivotally secured to the intermediate section, one at each end, engaging pins for the hooks secured to the back rest, a pair of rollers mounted on the end section, one at each end, a bracket having a guiding channel formed therein secured to each end frame of the davenport, said rollers extending into the channels and guided thereby, an offset formed in the upper end of each channel section adapted to receive the rollers and support the end frame when the mattress frame assumes a horizontal position, a pair of legs hingedly secured to the back rest adapted to support the back rest when in the horizontal position, and means connected with said legs for raising or lowering the main section of the mattress frame within the back rest.

4. In a davenport, the combination with a pivotally mounted back rest, of a mattress frame mounted on the rear side of the back rest, said mattress frame consisting of a plurality of pivotally connected sections, means controlled by the swinging movement of the back rest for folding said mattress frame sections when the back rest is swung to a substantially vertical position and causing said frame sections to assume a horizontal position when the back rest is swung to a horizontal position, a pair of leg members hingedly secured to the front side of the back rest adapted to support said side of the back rest and the bed frame and adapted to be folded over the bed frame when the back rest is swung to the vertical position, means for supporting the other side of the bed frame when in the horizontal position, and means connected with said legs for raising or lowering the main section of the mattress frame within the back rest.

5. In a davenport, the combination with a pivotally mounted back rest, of a mattress frame mounted on the rear side of the back rest, said mattress frame consisting of a main section, an intermediate section and an end section, all pivotally connected, means controlled by the swinging movement of the back rest for folding said mattress frame sections when the back rest is swung to a substantially vertical position and causing said frame sections to assume a horizontal

- position when the back rest is swung to a horizontal position, and means for raising and lowering the bed frame within the back rest. 65
- 5 16. In a davenport, the combination with a pivotally mounted back rest, of a mattress frame mounted on the rear side of the back rest, said mattress frame consisting of a main section, an intermediate section and an 70 end section, all pivotally connected, means controlled by the swinging movement of the back rest for folding said mattress frame sections when the back rest is swung to a substantially vertical position and causing 75 said frame sections to assume a horizontal position when the back rest is swung to a horizontal position, means actuated by the folding movement of the frame sections for raising or lowering one end of the main section, a pair of legs hingedly secured to the back rest adapted to support it in the horizontal position, and means actuated by said legs for raising or lowering the opposite end of the main section within the back rest. 80
- 20 17. The combination with the back rest and the main mattress frame section mounted therein, of means for raising and lowering said frame section within the back rest, a pair of supporting legs hingedly secured to the back rest, said legs also adapted to serve as bedding clamps, and a pair of floating latches carried by the back rest adapted to engage the supporting legs and secure the same in locking position. 85
- 25 18. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, and means 90 permitting vertical movement of the latches when in locking position in unison with the main mattress frame section. 95
- 30 19. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, means permitting vertical movement of the latches when in locking position in unison with the main mattress frame section. 100
- 35 20. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, and means 105 permitting vertical movement of the latches when in locking position in unison with the main mattress frame section. 110
- 40 21. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, and means permitting vertical movement of the latches when in locking position in unison with the main mattress frame section. 115
- 45 22. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, means permitting vertical movement of the latches when in locking position in unison with the main mattress frame section. 120
- 50 23. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, means permitting vertical movement of the latches when in locking position in unison with the main mattress frame section. 125
- 55 24. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, means permitting vertical movement of the latches when in locking position in unison with the main mattress frame section. 130
- 60 25. The combination with the back rest and the main mattress frame section mounted therein, of means for raising and lowering said frame section within the back rest, a pair of supporting legs hingedly secured to the back rest, said legs also adapted to serve as bedding clamps, a pair of latches carried by the back rest, one on each side, said latches adapted to engage and secure the legs when in locking position, means permitting vertical movement of the latches when in locking position in unison with the main mattress frame section. 135
- 65 26. The combination with the back rest and the main mattress frame section mounted therein, of means for raising and lowering one end of said frame within the back rest, said means comprising a pair of supporting legs hingedly secured to the back rest, a pair of shoes supporting the mattress frame, and means actuated by the movement of the supporting legs for raising and lowering the shoes and the mattress frame supported thereby. 140
- 70 27. The combination with the end mattress frame section and the rollers carried thereby, of a pair of channeled bracket members in which the rollers travel, said channeled members being substantially vertical and having a horizontal extension near the upper end, stop lugs formed on the upper end of each channeled member, and lugs on the end frame engageable with the stop lugs to guide the rollers into and out of the horizontal channeled extensions. 145
- 75 28. In a davenport, a pair of end frames, a bedding box connecting said frames, a back rest, a pair of arms pivotally mounted between the end frames to which the back rest is secured, said arms permitting the back rest to be swung to assume a horizontal position above and forward of the bed box or a substantially vertical position behind the bed box, a mattress frame carried on the rear side of the back rest, and means for automatically raising the mattress frame with relation to the back rest when swung to a horizontal position. 150
- 80 29. In a davenport, a pair of end frames, a bedding box connecting said frames, a back rest, a pair of arms pivotally mounted between the end frames to which the back rest is secured, said arms permitting the back rest to be swung to assume a horizontal position above and forward of the bed box or a substantially vertical position behind the bed box, a mattress frame carried on the rear side of the back rest, means for automatically raising the mattress frame with relation to the back rest when swung to a horizontal position, said means comprising a pair of legs hingedly secured to the back rest, and means actuated by the unfolding of said legs for raising the mattress frame. 155
- 85 30. In a davenport, the combination with a pivotally mounted back rest, of a mattress frame mounted on the rear side of the back rest, said mattress frame consisting of a main section, an intermediate section and an end section, of pivotally connected means controlled by the swinging movement of the back rest for folding said mattress frame section when the back rest is swung to a substantially vertical position, and causing said frame sections to assume a horizontal position when the back is swung to a horizontal position, means actuated by the unfolding

movement in the frame sections for raising and lowering one end of the main section, a pair of legs hingedly secured to the back rest adapted to support it in the horizontal position, means actuated by said legs for raising the opposite end of the main section within the back rest when the legs are unfolded and for lowering the said main frame when the legs are folded, means for supporting the end section in a horizontal posi-

tion, and a pair of hook-shaped links adapted to support the intermediate section.

In testimony whereof I have hereunto set my hand in the presence of two subscribing witnesses.

CHARLES B. HALL.
